UNITED STATES PATENT OFFICE.

WILLIAM FRANCIS MCKENNA, OF NEW YORK, N. Y., ASSIGNOR TO CHARLES T. DAVIS,
OF NEW YORK, N. Y.

CONTAINER-COVER-MOUNTED CUTTER.

1,361,080.

Specification of Letters Patent.

Patented Dec. 7, 1920.

Application filed March 8, 1920. Serial No. 364,220.

To all whom it may concern:

Be it known that I, WILLIAM FRANCIS MCKENNA, a citizen of the United States, and resident of New York city, in the county 5 of Kings and State of New York, have invented certain new and useful Improvements in Container-Cover-Mounted Cutters, of which the following is a specification.

My invention relates to containers and to 10 a cutting device mounted on removable covers thereof.

There are numerous articles which may conveniently be packaged in bottles or similar containers with removable covers, and 15 which prior to use should be cut open or into pieces. One example of this kind is afforded by the poison tablet provided with a protective coating, such as is set forth in my application #305,174, it being necessary that 20 the outer coating of such tablets be ruptured or pierced to expose the contents thereof for use.

The necessity for cutting or piercing the outer part of the article, or for cutting the 25 article into pieces, may cause some inconvenience when such article is to be used, owing to the absence of a suitable cutting implement. Furthermore, while such implement might conceivably be inclosed in or 30 attached to the container, the necessity for providing a substantial handle therefor, especially when the article to be cut is relatively hard, would compel the use of a relatively bulky cutter. It would be obviously 35 impractical to mount this on the outside of the container; and it would take up too much space if placed within the container.

A primary object of my invention is to 40 avoid these difficulties and to solve the problems presented thereby, by providing a cutter carried by the usual bottle cork. With this arrangement, the cork may be employed as a handle or grip in using the cutter, thus facilitating the use of a relatively small 45 cutting member, which will occupy a very small space, the device being readily manipulated and always present at the time when it is needed.

In the preferred form disclosed, another 50 object is to produce a cutter which may be readily mounted on the ordinary cork without interfering with the usual construction and use of such cork.

A further object is to provide a cork 55 mounted cutter capable of cutting relatively

hard articles without damage to the cork or the engagement of the cutter therewith, caused by the heavy pressure necessarily employed in cutting such articles.

Another object of my invention includes 60 the solution of the problems involved in providing a suitable package for articles of the type requiring cutting or breaking before use, the tablets protectively coated in accordance with the above-mentioned patent 65 affording an example of such articles, and the construction disclosed being adapted for use with such tablets.

It is well recognized that the proper packaging of an article is highly important commercially, both for delivering the article to 70 the user in proper condition and for promoting convenience in the use of such article. This object, therefore, includes the provision of a package consisting of a bottle or similar container adapted to be closed normally 75 by a removable cork provided with cutting means, as this type of package is particularly advantageous in properly protecting and facilitating the use of articles such as 80 have been above indicated. Such a package permits the use of articles as needed, without interfering with the protection afforded the remaining articles by the package, and facilitates the opening, cutting or rupturing 85 of each article when removed, thus providing a very efficient and convenient arrangement.

Other objects and advantages of my construction will be apparent from the following description, taken in connection with the accompanying drawings, in which:

Figure 1 is a front view of a package embodying my invention, part of the container being broken away,

Fig. 2 is a perspective view of a cork with a cutter mounted thereon,

Fig. 3 is a plan view of the cutter and shields, and

Fig. 4 is a perspective view showing the 100 method of using the cutter.

The package illustrated in Fig. 1 includes a suitable container, such as bottle 10, provided with a removable closure, such as cork 11. The cutter 12 is mounted on cork 11, 105 preferably in position to project into the interior of bottle 10 when the cork is in position therein, this arrangement protecting the cutter when the bottle is closed.

It will be apparent that a great variety 110

of forms of cutter may be used, and may be mounted on the cork in various ways. In the form disclosed, I have employed a cutter 12 which includes a blade 13 having a sharpened edge, and a shank 14 adapted to be inserted in the cork, said shank preferably being provided with a pointed end 15 for this purpose.

While I have disclosed a cutter formed 10 of sheet metal and very simply and economically manufactured, it will be evident that my invention is not limited thereto, nor is it restricted to the use of a single shank 14 or to a cutter generally flat in form.

15 Furthermore, I do not wish to be limited to a single continuous cutting edge, as such cutting portion may obviously be varied in accordance with the form of cutter and the requirements of different particular uses.

20 I may provide means engaging the cork to prevent the cutter 12 from being forced thereinto farther than is desirable under the pressure of the cutting operation. For this purpose, I employ a shield 16 which may be 25 integral with or connected to, or separate from cutter 12. One form of shield which is simple and effective is in the form of a circular disk, as shown best in Fig. 3, and is provided with a central aperture 17 30 through which cutter 12 passes into the cork.

If desired, suitable means may be carried by or formed on cutter 12 to engage shield 16 and prevent cutter 12 from passing there- 35 through beyond a certain point, one convenient arrangement for this purpose including shoulders 18 on the edges of the cutter, this arrangement also providing a reduced shank 14 and facilitating the in- 40 sertion thereof into the cork without splitting or weakening the latter materially.

The method of use of the cutter depends upon the nature of the article employed. Fig. 4 illustrates a convenient method of 45 employing the cutter to cut open coated tablets of the type described in said application. For this purpose, it is simply necessary to place the tablet 19 upon a support, and, grasping the cork with one hand, force 50 the cutter downward into the tablet. With this arrangement, it will obviously be easy to subdivide the tablet or any other article with considerable accuracy if less than the whole article is required for use.

55 It will be readily seen from Fig. 4 that while the exposed portion of the cutter occupies but a relatively small space and will reduce the capacity of the bottle only to a negligible extent, the cork affords an ample 60 grip which may be grasped by the hand without inconvenience. Moreover, any force within reason may be exerted on the cutter, as the shield 16 distributes the pressure throughout substantially the entire area of 65 the end of the cork, preventing any possi-

bility of rupturing the cork within the limits of any reasonable use.

While I have described a preferred form, my invention is broader than the specific disclosure, and includes a great many variations which will be apparent to one skilled in the art. The form of cutter may be varied in a great many ways, and it may be mounted on the cork by various means, my invention not being restricted to the employment of means integral with the cutter for mounting it on the cork. Furthermore, shield 16 may obviously be formed in numerous ways, and may be adapted to coöperate with particular forms of cutters, it being obvious that the cutter and shield must be designed to fit each other if a separate shield is employed. I also consider the word "shield" to include members formed on or from said cutter adapted to resist the penetration of the cutter into the cork beyond a predetermined point.

It will also be evident that while I have described and illustrated a cutter mounted on the bottom or inner end of a cork, my invention is not restricted to this specific location of the cutter.

The form of cutter disclosed herein is especially adapted for use on corks of the ordinary type; but my invention, in its broad aspect, is not restricted to bottles or to the use of corks for carrying the cutter, as such cutter may be mounted upon any suitable readily removable cover, and other forms of container may be employed instead of a bottle.

Other variations in the exact form of my invention will be evident to those skilled in the art, and fall within the scope of my invention as set forth in this specification.

I claim:

1. A combined container closure and cutting implement for bottles and like containers, consisting of a stopper adapted for normally closing the opening of the container and provided with a metal blade extending from one end of the stopper and formed with a cutting edge of substantial length at the end of the blade remote from the stopper.

2. A combined stopper and cutting implement for bottles and like containers, consisting of a tapered stopper of round cross section adapted to coöperate with the bottle neck and provided with a relatively thin blade extending longitudinally from the small end of the stopper, the blade having a relatively long cutting edge at its end remote from the stopper.

3. A combined bottle stopper and cutting implement consisting of a bottle cork, a relatively thin metal blade having a shank inserted in one end of the cork, the blade being provided with shoulders resting against the end of the cork, the blade having

a cutting edge of substantial length at the end of the blade remote from the shank.

4. A combined bottle cork and cutting implement consisting of an approximately cylindrical cork and a thin knife blade having a shank extending into the cork from one end part way to the other end, shoulders extending laterally at the base of the shank and a cutting edge of substantial length at

the end of the blade remote from the cork, 10 and a separate washer apertured to receive the shank and placed between the end of the cork and the blade shoulders.

Signed at New York city in the county of Kings and State of New York, this 3rd day 15 of March, A. D. 1920.

WILLIAM FRANCIS McKENNA.
